UNITED STATES PATENT OFFICE.

MELVIN RICHEY, OF SHREVE, AND SILAS JACKSON CRITES, OF JEROMEVILLE, OHIO.

SLIDING-DOOR HANGER AND HOOD.

No. 923,706

Specification of Letters Patent. Patented June 1, 1909.

Application filed January 11, 1909. Serial No. 471,700.

To all whom it may concern:

Be it known that we, MELVIN RICHEY, a citizen of the United States, residing at Shreve, county of Wayne, State of Ohio, and 5 SILAS JACKSON CRITES, a citizen of the United States, residing at Jeromeville, in the county of Ashland and State of Ohio, have invented certain new and useful Improvements in Sliding-Door Hangers and 10 Hoods; and we do declare the following to be a full, clear, and exact description of the invention, such as will enable others skilled in the art to which it appertains to make and use the same.

15 This invention relates to the construction of a combined hood and hanger for sliding doors.

One of the objects of the invention is the production of a combined hanger and hood 20 capable of being made in sections and arranged to slidably support a door upon a rain protected track secured to the hood.

With this and other objects in view, the invention consists of certain novel features 25 of construction, combination and arrangement of parts as will be more fully described and particularly pointed out in the appended claims.

In the accompanying drawings, Figure 1 30 is a front elevation of our improved combined hood and hanger; and Fig. 2 is a vertical sectional view thereof.

In the accompanying drawings, numeral 1 designates a hood which is provided with a 35 depending outwardly bent flange 2 adapted to cover the upper edge of the door. The hood 1 is also formed with an upwardly projecting flange 3 which is adapted to be secured to a door frame in any suitable manner. On the inner side of the depending flange 2 a track 4 which is substantially 40 U-shaped in cross section is secured thereto by means of rivets 5. A brace 6 is secured by a rivet 7 at its upper end to the upper end 45 of the vertical flange 3 and extends for a portion of its length at an oblique angle and is connected at its lower end to the depending flange 2 by the rivets 7 and is constructed wide enough so as to overlap and connect 50 with a second duplicate section of the hood.

The track 4 is adapted to receive a wheel 8 which is rotatably mounted in a U-shaped

wheel hanger arm, 9, formed with a curved end, 10. The curved end 10 is connected by means of a link 11 with a hanger 12 having depending spaced legs 13 which are adapted to straddle a door 14 in the customary way.

In order to prevent the link 11 from wabbling on the hanger 12, said hanger is 60 formed with a groove 15 forming a seat for said link. When rain or rubbish falls upon the hood 1 which is formed with a slight incline, said rain or rubbish will ride thereoff and pass over the outer surface of the 65 depending flange 2 without in any way contacting with the upper edge of the door thereby protecting said door and the hanger from becoming injured in any way.

From the foregoing description, taken in 70 connection with the accompanying drawings, the construction and operation of the invention will be readily understood without requiring a more extended explanation.

Various changes in the form, proportion 75 and the minor details of construction may be resorted to without departing from the principle or sacrificing any of the advantages of the invention as defined in the appended claim.

Having thus described and ascertained the nature of our invention, what we claim as new and desire to secure by Letters-Patent is:

In a device of the class described, a hood 85 formed with vertically arranged and depending flanges substantially parallel, said depending flange having its lower end bent outwardly, a track secured to the inner side of the depending flange above the lower edge 90 thereof, a brace secured to the vertical and depending flanges diagonally above the hood and adapted to overhang the vertical ends of said flanges to connect adjoining sections, and a door movably mounted on the track 95 and overlapped by the depending flange.

In testimony whereof we have hereunto set our hands in presence of two subscribing witnesses.

MELVIN RICHEY.
SILAS JACKSON CRITES.
